SASH FASTENER AND LIFT.

1,194,775.

Specification of Letters Patent. Patented Aug. 15, 1916.

Application filed September 4, 1912. Serial No. 718,587.

To all whom it may concern:

Be it known that we, OSCAR OEHRING, technical manager, and GEORG HEUER, manufacturer, subjects of the Kings of Prussia and Saxony, respectively, residing at Eisenleben, Germany, and Dresden, Saxony, Germany, respectively, have invented certain new and useful Improvements in Sash Fasteners and Lifts, of which the following is a specification.

This invention relates to an improvement in sash raising and lowering mechanism, and has for its object to provide an improved mechanism wherein but one handle is employed for releasing the sash or window frame for raising or lowering the sash or pane into the desired position, and subsequently to secure the sash or pane in the adjusted position.

Other objects and advantages of this invention will appear from the following detail disclosure of the present embodiments of the invention, the same being disclosed in the accompanying drawings wherein,—

Figure 1 is an elevation of one form of the device of this invention, showing one of the side plates removed to disclose the inner mechanism; Fig. 2 discloses in elevation and in section a slightly modified form of the device. Fig. 3 shows in elevation and in horizontal section a further modification of the device of this invention, an edge view of the rotary element being also disclosed. Fig. 4 is a vertical section of another modification of the invention taken on the line A—A of Fig. 5. Fig. 5 is an elevation of the same. Fig. 6 is a vertical section similar to Fig. 4 but showing a slightly modified form thereof. Fig. 7 is a transverse section taken on the line B—B of Fig. 6. Fig. 8 is a view similar to Fig. 6 showing a further modified form of the clamp releasing means.

Referring particularly to Fig. 1 of the drawings the sash or pane 1 is mounted in a frame which may be in the form of a door or the like, and which is provided with a well 10 into which the sash or pane 1 may be dropped for opening the window. At one side of the well 10, and secured to the main frame, are a pair of spaced apart plates I and II in which are mounted a transverse shaft 62, the latter extending at its opposite ends through the plates. The shaft 62 is

provided upon its outer end with a handle 46 for turning the shaft 62.

Between the plates the shaft 62 has fixed thereon a ratchet disk 64 the teeth of which are rounded or beveled for a purpose which will hereinafter appear. A toothed segment 66 is mounted to turn upon the shaft and is provided with a slightly elongated slot receiving a pin 65 projecting laterally from the ratchet disk 64, the pin 65 and the slot constituting a loose connection between the disk 64 and the segment 66 admitting of a slight initial movement of the disk 64 prior to moving the segment and its parts. The segment 66 is provided with a radially extending arm 45 hinged at its outer end to a bar 42 extending down into the well 10 and having pivotal connection at 41 with the closed portions of a pair of arms of the lazy tongs 39. The lower end of the lazy tongs 39 terminates in a pair of links 100 having upon their lower ends offset hooks 101 receiving the inner ends of contracting springs 102. The outer ends of the springs 102 are fixed in the opposite ends of a bracket 103 secured in the bottom of the well 10. The lower ends of the links 100 are pivotally connected by a cross piece 104 and by means of studs 105 carried by the bracket 103 and hingedly engaging through the ends of the links 100, and the ends of the cross-piece 104. By this arrangement the springs 102 normally urge the lazy tongs into expanded position and act as counter-balances for the sash or pane 1 which is secured and supported upon the upper end of the lazy tongs 39 by means of a strip 106.

Between the plates I and II is pivoted a pawl 67 yielding urged against the teeth of the ratchet disk 64 and the segment 66 by a spring 68. When the disk and the segment are in the relative positions shown in Fig. 1 the beveled or rounded teeth of the disk 64 are in alinement with the throats of the teeth of the segment 66 and support the pawl 67 out of engagement with the teeth of the segment 66. When in this position the segment 66 may be swung in the direction opposite to that indicated by the arrow in Fig. 1, to expand the lazy tongs 39 and raise the sash. The slot in the segment 66 is of such length that when the pin 65 is moved into the opposite end of the

slot the beveled teeth of the ratchet disk 64 are moved a distance equal to the width of a tooth so as to register the same with the next succeeding throats of the teeth of the segment 66. By this arrangement the handle 46 may be swung in the direction indicated by the arrow in Fig. 1 to first register the teeth of the disk and the segment and admit of the engagement of the pawl 67 with the teeth of the segment to lock the same from movement, and subsequently raise the pawl 67 out of engagement with the teeth and place the same in a position to be rotated in the direction of the arrow for lowering the sash or pane 1.

Above the well, and in the inner side of the main frame, is disposed a clamping frame 89 the same being suitably supported whereby the lower end thereof may be swung toward and from the sash or pane 1 so as to clamp the sash from rattling or release the same when it is desired to operate it. This clamping frame 89 is provided with a finger 107 depending therefrom within the well and adjacent to the inner plate II. The shaft 62 carries upon its inner end a clamping arm 69 adapted to be swung up into vertical position when the operating handle 46 is raised to lower the sash 1. The arm 69 is provided with a rounded projection adapted for engagement between the finger 107 and the plate II to force the finger 107 inwardly, move the frame 89 therewith and thus bind the sash 1 from rattling or from accidental movement during the vibration of the main frame. For facilitating the engagement of the arm 69 beneath the finger 107 the latter is provided with a beveled lateral edge 72 which produces the clamping action of the arm 69 when moving the clamping frame against the sash. Thus after the handle 46 has been moved to adjust the sash 1 into the desired lowered position the arm 69 is brought into position by the handle to clamp the frame 89 against the sash 1 and thus lock the sash in its adjusted position.

In Fig. 2 a slight modification of this structure is disclosed wherein the segment 64^a has a smooth periphery with a recess or notch in one side thereof, preferably in alignment with the handle 46 and wherein the disk 64^a is of slightly greater diameter than the segment 66^a. The pawl 67^a slides upon the smooth periphery of the disk 64^a until it reaches the notch 71 when the pawl is permitted to drop into engagement with the teeth of the segment 66^a. The segment 66^a has an elongated concentric slot 70 into which projects the pin or stud 65 carried upon the disk 64^a and which permits of the free movement of the handle 46 for a considerable distance to lock and unlock the sash 1 by means of the arm 69 prior to engaging the pawl 67^a with the segment 66^a.

to hold the sash from vertical movement. By this arrangement the clamping frame 89 may be operated upon practically any adjustment of the sash within the frame so as to secure the sash from rattling when the same is lowered into practically any desired position. It is thus seen that in this modified form of this invention, the handle 46 is also common not only to the means for raising and lowering the sash but also to the means for clamping the sash when adjusted.

In Fig. 3 of the drawings a further modified form of the invention is disclosed wherein the handle 46 controls the raising and lowering of the window as well as the clamping of the same when it is adjusted.

As will be noted from Fig. 3 the shaft 62 upon which the handle 46 is mounted is provided between the plates I and II with a disk 73 having a stud 65^a passing entirely through the disk and extending beyond the opposite sides thereof. Loosely upon the shaft 62, and against the outer side of the disk 73, is a lever 45^a connected to the lazy tongs 39 at its outer end and having upon its inner end a projection 108 in line with the outer end of the stud 65^a. For raising and lowering the window a handle 46 is moved to turn the shaft 62 and thus rotate the disk 73 to move the outer end of the stud 65^a against the projection 108 to swing the lever 45^a in the direction opposite to that indicated by the arrow in Fig. 3 to expand the lazy tongs 39 and thus raise the sash 1. The outer end of the stud 65^a is also adapted to be moved into engagement with the long arm of the lever 45^a to press the same down and collapse the lazy tongs to thus move the sash down into the well.

The means for clamping the sash in position when adjusted comprises a pair of fingers 75 extending downwardly from the opposite ends of the clamping frame 89 and having beveled or rounded edges adapted to receive thereagainst correspondingly formed abutments 74 mounted on the opposite ends of a sliding bolt 109. The bolt 109 is mounted upon the plate II and has fixed to its middle portion a slotted plate 110. The plate 110 projects down toward the shaft 62 and has intermediate its ends a vertical slot 111 adapted to receive the inner end of the stud 65^a when the disk 73 is turned. When the stud 65^a enters the slot 111 the stud moves the plate 110 and the bolt 109 from the position shown in full lines in Fig. 3 to the central position shown in dotted lines in the same figure. This movement of the bolt 109 brings the abutment 74 into contact with the fingers 75 to thereby force the fingers inwardly and move the clamping frame 89 against the sash. Further movement of the handle 46 in the direction indicated by the arrow in Fig. 3 moves the plate 110 toward

the left, disengages abutments 74 from the fingers 75 and moves the inner end of the stud 65^a out of the slot 111.

For the purpose of retaining the plate 110 in proper position to register the slot 111 with the stud 65^a when the latter has moved away from the plate in the operation of the lever 45, the plate 110 is provided at its opposite ends with curved slots 112 conforming to the curvature of the disk 73 and adapted to be moved into position concentric with the disk 73 by the stud 65 after the latter leaves the plate. A pair of pins 113 project inwardly from the disk 73 and engage in the curved slots 112 when the stud 65 leaves the slot 111, the pins 113 being employed for the purpose of holding the plate 110 from accidental movement, by vibration or the like, until the stud 65^a is again engaged in the slot 111. From Fig. 3 it will be noted that one of the pins 113 is entering one of the curved slots 112 while the stud 65^a is about to leave the slot 111 in order to actuate the lever 45^a.

Referring now to the modification disclosed in Fig. 4, it will be noted that the main frame is provided in one side of the well with a sprocket wheel 81 fixed upon a hub 90 which is journaled for rotation in the main frame, and which is provided at its outer end with a pair of ears pivotally supporting between them the handle 46^a. The inner end of the handle is formed into a cam 91 having at its center a notch 92 for the purpose which will hereinafter appear. The hub 90 is hollow and contains a rod 87 adapted for longitudinal sliding movement in the hub 90, and a helical spring 88 surrounds the rod 87 abutting at one end 40 against a detachable disk 114 closing the inner end of the hub. The opposite end of the spring 88 bears against a stop 115 fixed upon the rod 87 near the outer end of the hub. The rod 87 projects beyond the disk 115 and through the hub into the space between the ears on the hub and is adapted to bear against the cam 91 and to move into the notch 92 when the handle is swung up into horizontal position. The inner end of the rod 87 is pivoted to the fork arm 85, the arms of which are pivoted as at 86 to the main frame and are adapted to swing about by pivots when the rod 87 is forced inwardly by the cam 91. The lower end of the fork arm projects below the hub and is turned in to provide a friction stop 84. The stop 84 in Fig. 4 is shown as an inturned finger while in Fig. 5 the stop is shown as a roller 84^a. The sprocket wheel 81 is provided with an annular groove for the reception of the friction stop 84 which latter is yieldingly held in the groove by the spring 88 and the rod 87. The sash or pane 1 is connected by a rod 82 to a chain 80 passing over the sprocket wheel 81 and down into the well.

When the sprocket wheel is turned, by turning the handle 46^a, the chain 80 is moved over the sprocket wheel and caused to raise or lower the sash as is desired. The sash is held in clamped position by the clamping frame 89 which, as shown in Fig. 4, normally bears against the sash 1 to hold it firmly in place. The upper ends of the arms of the fork lever 85 above the pivots 86 lie in the path of a flange or finger 118 projecting down from the bottom of the clamp frame 89. With this construction it is readily seen that when the handle 46^a is raised into horizontal position the cam 91 forces the rod 87 inwardly against the tension of the spring 88 to rock the lever 85 about its pivotal supports 86 to not only withdraw the friction stop 84 from the sprocket wheel 81 and thus free the sprocket, but also for bringing the upper ends of the fork lever 85 into contact with the flange or finger 118, and to move the same outwardly to thus carry the clamping frame 89 therewith and release the sash 1. As the sprocket wheel 81, and the sash 1 have now been released the handle 46 may be turned to rotate the hub 90 and sprocket wheel 81, and to thus operate the chain to raise or lower the sash 1 as desired. As soon as the proper adjustment of the sash is had the handle 46^a is again swung down, or to one side, to release the rod 87 and admit the spring 88, drawing outwardly the lower end of the forked lever 85 to release the clamping frame 89 and frictionally hold the sprocket wheel 81 from turning. It is thus seen that by the operation of a single handle the raising and lowering means for the window is controlled, and also that the means for clamping the window when adjusted is controlled.

In Figs. 6 and 7 of the drawings a slightly different form of operating mechanism is shown wherein the hub 90^a carries a sprocket wheel 81^a to effect the raising and lowering of the sash as in the construction shown in Fig. 4. The sprocket wheel 81^a is provided upon its outer side with a cam groove 83^a in which rides a roller 117. The roller 117 is journaled in a stud 118 slidably in a guide-way 93 fixed to the main frame. The stud 118 is provided, as best shown in Fig. 7, with a pair of oppositely extending fingers 98 engaging the lower ends of a forked arm 99 projecting downwardly from the clamping frame 89. A spring 95 is mounted in the casing 93 and bears at its outer end against the stud 118 to normally and yieldingly urge the stud outwardly toward the sprocket wheel 81^a. As the roller 117 travels in the cam groove 83^a it reciprocates with the stud 118 in the casing 93. When the stud 118 is retracted in the casing 93 the fingers 98 of the stud engage the lower ends of the arm 99, carrying the arm 99 for-

wardly and moving the clamping frame 89 from the sash 1.

In Fig. 8 of the drawing the clamping frame 89 is provided with a depending arm 99^a carrying in its lower end a horizontal roller 117 bearing against the sprocket wheel 81^a in the same manner as disclosed in Fig. 6. In this latter case the spring and retracting stud are omitted and the roller is carried directly upon the clamping frame and the usual means for urging the clamping frame against the sash 1 is utilized for holding the roller 117 against the sprocket wheel.

What is claimed is:

15 1. In combination with a window frame and a sash therein, hoisting means for the sash, clamping means for the sash, locking means for said hoisting means, and means common to said means for actuating all of

20 2. In combination with a window frame and a sash therein, raising and lowering mechanism in the frame having connection with the sash, clamping means on the frame 25 for engagement with the sash, means for locking said raising and lowering means in adjusted position, and a handle for said raising and lowering means, clamping means, and locking means, said handle operating these means to raise and lower the sash.

3. In a device as specified, a main frame, a vertically movable sash in the main frame, means for raising and lowering said sash in 35 the frame, locking means for securing said raising and lowering means in adjusted position, clamping means on the main frame for securing the sash when adjusted, and a handle common to said raising and lowering 40 means, locking means and said clamping means adapted when operated to first release the sash and said raising and lowering means and to subsequently raise and lower the sash.

45 4. In a device as specified, a main frame, a vertically movable sash in the frame, means

for clamping the sash in the frame, raising and lowering means connected to the sash, locking means for securing said raising and lowering means in adjusted position, and a handle operatively connected to said clamping means, locking means and raising and lowering means adapted to release said clamping means from said sash and said locking means from said raising and lowering means, to raise and lower the sash, and to again clamp the sash and lock said raising and lowering means in adjusted position.

5. In combination with a window frame and a sash therein, hoisting means for the sash, locking means for securing the hoisting means in adjusted position, clamping means for securing said sash against rattling, and a handle common to said means adapted to actuate said locking means and clamping 65 means to permit operation of said hoisting means and to subsequently lock said hoisting means and bring said clamping means against said sash.

6. In combination with a window frame 70 and a sash, hoisting means for the sash including a rotary part, a handle connected to said rotary part for turning the same to raise and lower the sash, clamping means connected to said handle, and locking means 75 for securing said rotary part in adjusted position, said handle being adapted to release said clamping means and to actuate said locking means to release said rotary part to raise or lower the sash.
